UNITED STATES PATENT OFFICE.

WILLIAM T. HANNA, OF CINCINNATI, OHIO.

RECIPROCATING ENGINE.

Application filed August 6, 1921. Serial No. 490,329.

To all whom it may concern:

Be it known that I, WILLIAM T. HANNA, a citizen of the United States of America, and a resident of Cincinnati, in the county of Hamilton and State of Ohio, have invented a new and useful Improvement in a Reciprocating Engine, of which the following is a specification.

My invention relates to engines of the reciprocating type.

An object of my invention is to provide a simple and efficient means to change the flow of steam into the cylinder on opposite sides of the piston upon the arrival of the piston at the opposite ends of its stroke.

Another object of my invention is to provide an engine of the type referred to where in the stroke may be reversed intermediate the ends thereof.

Another object of my invention is to provide a device of the type referred to for the purposes stated that is simple in construction and operation.

These and other objects are attained by the means described herein and disclosed in the accompanying drawings, in which—

Fig. 1 is a side elevation of an engine embracing my invention.

Fig. 2 is a sectional view on line 2—2 of Fig. 6.

Fig. 3 is a sectional view on line 3—3 of Fig. 1.

Fig. 4 is a sectional view on line 4—4 of Fig. 2.

Fig. 5 is a sectional view on line 5—5 of Fig. 2.

Fig. 6 is a sectional view on line 6—6 of Fig. 2.

Fig. 7 is an enlarged view of a sleeve forming a detail of my invention looking thereat as indicated by the double headed arrow in Fig. 2.

Fig. 8 is an end view of the sleeve shown in Fig. 7.

Fig. 9 is a view showing the reversing valve in a position opposite to that shown in Fig. 5.

My invention comprises a reciprocating engine having the piston control valve D' adapted to reverse the stroke of the piston upon the completion of the piston stroke, and an auxiliary reverse valve B adapted to reverse the stroke of the piston intermediate the ends of the piston stroke.

The engine A comprises a cylinder a hav-

ing at its opposite ends the cylinder heads a^1 and a^2 whereby a cylinder chamber a^4 is formed. The cylinder a has formed upon it a valve housing a^5 within which is disposed the auxiliary reverse valve or secondary valve B. The housing a^5 has formed within it a cylindrical chamber a^6 extending transversely of the line of reciprocation of the piston. A duct a^7 communicates with the chamber a^6 and with the chamber a^4 adjacent the cylinder head a^2 . A second duct a^8 communicates with the chamber a^6 and the chamber a^4 adjacent the opposite cylinder head a^1 . The ends of the chamber a^4 are slightly enlarged as a result of the tapering bores a^9 , and the ducts a^7 and a^8 communicate with these enlarged portions of the cylinder chamber by means of a series of small auxiliary ducts a^{10} . The duct a^7 communicates with the chamber a^6 by way of an annular groove a^{11} formed in the housing a^5 and the duct a^8 communicates with the chamber a^6 by way of an annular groove a^{12} formed in the housing a^5 . An annular groove a^{13} is formed in the casing a^5 intermediate the annular grooves a^{11} and a^{12} , and communicates with a duct a^{14} formed in the cylinder wall and with a duct a^{15} extending through the cylinder head a^2 . A fourth annular groove a^{16} is formed within the housing a^5 and is spaced from the groove a^{13} by the groove a^{12} and communicates with a duct a^{17} formed within the cylinder wall and with a duct a^{18} extending through the cylinder head a^2 . A plate a^{19} is mounted on one end of the housing a^5 and forms a closure for said one end of the chamber a^6 . The plate a^{19} has an axial bore a^{20} adapted to permit reciprocation therethrough of a rod, the purpose of which will be explained hereafter. The opposite end of the housing a^5 has a screw threaded bore a^{21} in alignment with the bore in the plate a^{19} and with the axis of the chamber a^6 . A cap a^{22} engages in the threaded bore a^{21} and forms a closure for the end of the chamber. A suitable drain cock a^{23} may be mounted upon the housing a^5 to permit draining of the products of condensation. An angle plate a^{24} is mounted upon the cylinder a and has pivotally mounted upon it a lever b . The plate a^{24} has formed upon it suitable notches a^{25} wherein the lower end of the spring actuated lock rod b' mounted on the lever, may engage in order

2 to retain the lever in an adjusted position in a manner that is common and well known in the art.

The auxiliary or secondary valve mechanism B comprises a valve member b^2 slidably mounted within a sleeve b^7 mounted within the bore in the housing a^5 . The valve member is cylindrical in form and has an axial bore b^8 formed therethrough. A spider b^4 is formed at each end of the valve member and provides means whereby the valve member may be mounted upon the reciprocating rod b^5 extending through the axial bore a^{18} in the plate a^{17} . The cylinder has formed in it a circumferential groove b^6 . The portions of the cylinder on either side of the groove b^6 provide bearing surfaces which ride upon the inner wall of the sleeve b^7 mounted in the chamber a^6 . The sleeve b^7 has formed within it a series of slots b^8 , registering with the annular grooves a^{11} , a^{12} , a^{13} and a^{15} . From the foregoing it is apparent that the slots in the sleeve provide communication between the annular grooves and the chamber a^6 . The opposite ends of the chamber a^6 communicate with one another thru the valve member b^2 by way of the axial bore b^8 and the spaces between the arms of the spiders. The circumferential groove b^6 in the valve member b^2 is of such length that communication may be established therethrough between any two adjacent annular grooves in the housing a^5 . The reciprocating rod b^5 has its one end pivotally mounted upon the lower end of the lever b . The other end of the reciprocating rod is preferably of reduced diameter whereby a shoulder b^9 is formed thereupon and against which shoulder the valve member is retained by means of the lock nuts b^{10} mounted upon the threaded end of the rod b^5 . The cap a^{20} acts as a stop for rod b^5 in aligning the circumferential groove with the annular grooves a^{12} and a^{15} or for any purpose that may make such access desirable or necessary. From the foregoing it is apparent that the valve member b^2 may be employed to establish communication between the annular grooves a^{12} and a^{15} , or between the annular grooves a^{12} and a^{13} , that when a^{12} and a^{15} communicate, the grooves a^{11} and a^{13} communicate, and that when a^{12} and a^{13} communicate the grooves a^{11} and a^{15} communicate, depending upon the position of the valve member b^2 .

The cylinder head a^2 has formed in it a bore a^{21} extending in axial alignment with the cylinder a . The end of the bore a^{21} farthest removed from the cylinder chamber a^4 is enlarged, the shoulder a^{22} being formed at the junction of the enlarged and reduced portions of the bore. A duct a^{23} extends through the cylinder head and establishes communication between the chamber a^4 and the enlarged portion of the bore 7 and 8. The sleeve has formed in its outer

a^{21} . A bore a^{24} is formed in the cylinder head a^2 below the bore a^{21} and transversely thereto. Within the bore a^{24} are disposed the elements comprising the primary valve D', and within the bore a^{21} are disposed the elements comprising the pilot valve controlling mechanism D.

The valve controlling mechanism D comprises a cylindrical collar or sleeve d which is disposed within the bore a^{21} and provides a bearing for the reciprocating rod d' . The sleeve d has a reduced end which projects through the reduced portion of the bore a^{21} . This sleeve has an annular bore d^2 , the diameter of which is reduced at the smaller end of the sleeve. A shoulder d^3 formed upon the sleeve at the junction of the enlarged and reduced portions of the sleeve abuts the shoulder a^{22} extending into the bore a^{21} . A groove d^4 is formed in the shoulder d^3 and communicates with the duct a^{23} . A screw cap d^5 is mounted on the cylinder head and forms a closure for the end of the enlarged portions of the bore a^{21} and for the chamber d^6 formed within the sleeve d . The cap d^5 has a bore d^7 in alignment with the axis of the cylinder. The rod d' is adapted to be reciprocated in the bore d^7 . A circumferential groove d^8 is formed at the junction of the sleeve d , the cap d^5 and the cylinder head a^2 . This circumferential groove communicates with the groove d^4 by means of a duct d^9 extending longitudinally through the sleeve d , and also communicates with the bore d^7 by way of the duct d^{10} formed in the cap d^5 . From the foregoing it is apparent there will be uniform pressures in the bore d^7 and the cylinder chamber a^4 . The rod d' has formed upon it, internally to the chamber d^6 , the shoulders d^{11} and d^{12} , between which shoulders is formed a reduced portion d^{13} . A sliding valve d^{14} , having branches d^{15} and d^{16} , is disposed within the chamber d^6 and has its branches extending on opposite sides of the reduced portion d^{13} of the rod. The ends of the valve d^{14} abut the shoulders d^{11} and d^{12} , wherefore, when the rod d' is reciprocated, the sliding valve is likewise reciprocated. The valve has a notch d^{17} formed in its lower surface, the purpose of which will be explained hereafter. A portion of the rod d' extends into the cylinder chamber and has formed at its end a head or button d^{18} , the purpose of which will be explained hereafter. Suitable pins d^{19} , extending through the valve head a^2 and the sleeve d , may extend between the branches d^{15} and d^{16} of the slide valve d^{14} and serve to prevent lateral movement of the slide valve and the sleeve d .

The primary valve D' is disposed in the bore a^{24} . The bore a^{24} has mounted within it a sleeve d^{19} . This sleeve is shown in Figs. 7 and 8. The sleeve has formed in its outer

wall a slot d^{20} which communicates at one end with the axial bore d^{21} extending through the sleeve, and at its other end with a duct d^{22} formed in the cylinder head a^2 and communicating with the chamber d^6 . A second groove, d^{23} , is formed in the sleeve d^{19} and communicates with the bore in the sleeve d^{19} at one end and with a second duct, d^{24} , in the cylinder head a^2 . The duct d^{24} 10 communicates with the chamber d^6 . Another groove d^{25} formed in the sleeve d^{19} communicates with the chamber d^6 by way of a duct d^{26} formed in the cylinder head a^2 . The ducts d^{22} , d^{24} and d^{26} extend through the 15 sleeve d and are disposed in such relation to one another that when the sliding valve d^{14} is reciprocated, the valve d^{14} may cause the ducts d^{24} and d^{26} to communicate by way of the groove d^{17} therein, while the valve seals the duct d^{22} , or the duct d^{24} may be sealed 20 by the valve d^{14} , while the duct d^{22} is exposed to and communicates with the chamber d^6 . The sleeve d^{19} has formed in it an exhaust port d^{27} extending therethrough and with 25 which the groove d^{25} communicates. The bore within the sleeve d^{19} provides a chamber d^{28} therein. The chamber d^6 communicates with the chamber d^{28} formed within the sleeve d^{19} by way of the duct d^{29} extending 30 through the sleeve d , the cylinder head a^2 and the sleeve d^{19} . An intake port d^{30} formed within the sleeve d^{19} communicates with a suitable source of energy by means of the bore d^{31} formed in the cylinder head a^2 35 and which may communicate by means of a suitable pipe d^{32} , with a boiler, not shown. The exhaust port d^{27} communicates with a suitable exhaust, such as the pipe d^{33} . Upon opposite sides of the exhaust port d^{27} are 40 formed intake ports d^{34} and d^{35} respectively, which communicates with the bore in the sleeve d^{19} . The port d^{34} communicates with the duct d^{37} formed in the cylinder head a^2 and which duct communicates with the duct 45 d^{16} formed in the cylinder wall a . The port d^{35} communicates by means of a duct d^{36} with the duct d^{14} formed in the cylinder wall a . The bore d^{21} formed within the sleeve d^{19} is reduced in part. Within the reduced 50 part of the chamber d^{28} , formed by the bore, is mounted a sliding valve d^{38} constructed substantially like the sliding valve d^{14} . This valve has a cavity d^{39} whereby the exhaust port d^{27} may be placed in communication 55 with either of the ports d^{34} or d^{35} . The valve d^{38} is held in position by means of a reciprocating rod d^{40} . The branches d^{41} and d^{42} of the valve d^{38} extend over opposite sides of the rod d^{40} . A piston d^{41} is mounted upon 60 the rod d^{40} and is disposed within the enlarged portion of the chamber d^{28} . The enlarged portion of the chamber is of sufficient length that the movement of the piston d^{41} from one end to the other thereof will provide 65 sufficient movement of the valve d^{38} so

as to cause one or the other of the ports d^{34} or d^{35} to communicate with the exhaust port d^{27} . A plate d^{42} is mounted upon the cylinder head a^2 and forms a closure for the enlarged end of the chamber d^{28} . The groove d^{20} in the sleeve d^{19} communicates with the space that is left between the plate d^{42} and the piston d^{41} when the piston is moved to the position as shown in Fig. 6. In order to assure the ready admission of steam between the piston d^{41} and the plate d^{42} , it is preferable to enlarge the mouth of the enlarged portion of the bore in the same manner as are the ends of the chamber a^4 enlarged, as shown at a^9 in Fig. 2. A plate d^{43} forms a closure for the other end of the chamber d^{28} and has formed within it a bore d^{44} in axial alignment with the rod d^{40} . A piston d^{45} is mounted upon the rod d^{40} and is adapted to be reciprocated within the bore d^{44} formed 80 in the plate d^{43} , the diameter of the bore d^{44} being substantially smaller than the diameter of the enlarged portion of the chamber d^{28} . The surface of the piston d^{45} being smaller than d^{41} , therefore when steam acts 90 upon them there is an inequality of pressure which will serve to reciprocate the rod d^{40} in a manner which will be explained more fully hereafter.

The piston C is adapted to be reciprocated within the chamber a^4 and is mounted upon the piston rod c extending through the cylinder head a' . The piston rod is preferably a tube shaft into which the rod d' may extend. A plate c' is mounted upon the piston and has a slot c^2 therein. The slot is so disposed in relation to the bore c^3 in the tube shaft that part of the plate extends partly over the bore c^3 . The tube shaft c has a notch c^4 formed therein opposite to the portion of the plate extending over the bore c^3 , the notch c^4 being substantially co-extensive with the upper end of the slot c^2 in the plate c' . The purpose of this construction is to permit the ready insertion and removal of the button d^{48} on the rod d' into and from the bore c^3 in the tube shaft. The portion of the plate c' extending over the bore c^3 is adapted to engage the button on the movement of the piston away from the mechanism D , whereby the rod d' may be longitudinally actuated. When the piston moves toward the mechanism D , the plate c' abuts the shoulder d^{47} formed on the rod d' and serves to actuate the rod d' longitudinally.

The operation of my device is as follows:

We will assume that the parts are in the relation shown in the drawings. The piston C has just moved to its farthest limit from the mechanism D and the rod d' has been 125 longitudinally actuated so as to cause the sliding valve d^{14} to seal the duct d^{22} and to place ducts d^{24} and d^{26} in communication. The chamber d^{28} is filled with steam entering 130 thereinto by way of the duct d^{31} . As a re-

sult of the ducts d^{24} and d^{26} having been placed in communication, the piston d^{41} has been moved to the position shown in Fig. 6 by the steam within the chamber d^{28} acting 5 upon the unequal exposed faces of the opposed pistons d^{41} and d^{45} , and the space intermediate piston d^{41} and plate d^{42} is in communication with the exhaust via d^{23} , d^{24} , d^{26} and d^{25} , (see Fig. 7). Some of the steam 10 within the chamber d^{28} will then pass into chamber a^6 by way of the port d^{34} , and the ducts d^{37} and a^{19} and annular groove a^{16} . The steam enters that portion of the chamber a^6 contained between the walls of the circumferential groove b^6 in valve member b^2 , and the sleeve b^7 , and from thence passes into the duct a^8 , and will then act upon that face of the piston C immediately adjacent the cylinder head a' , wherefore the piston C will be 15 moved toward the mechanism D. When the plate c' abuts the shoulder d^{47} on the rod d' , the sliding valve d^{44} is actuated so as to seal the duct d^{24} and to open the duct d^{22} . Therefore the steam contained within the 20 chamber d^6 will pass thru the duct d^{22} and slot d^{20} into the space between the piston d^{41} and the plate d^{42} . The steam pressures on the opposite faces of the piston d^{41} being then neutralized, the steam within the chamber d^{28} acting upon the piston d^{45} will move 25 the rod d^{40} longitudinally as the space d^{44} is in communication with the atmosphere through a small vent d^{400} . The sliding valve d^{38} will close off the flow of steam through 30 the port d^{34} , and place the port d^{35} into communication with the exhaust d^{27} . At the same time the port d^{36} is placed into communication with the chamber d^{28} and the steam within the chamber d^{28} will then pass 35 through the port d^{35} , the ducts d^{33} and a^{14} and enters into the chamber a^6 by way of annular groove a^{12} . The steam entering the chamber a^6 then passes, by way of annular groove a^{11} , through the duct a^7 and operates 40 upon the opposite side of the piston C, thereby reversing the stroke of the piston. As the piston C reaches its limit, as shown in Fig. 2, the engagement of the button d^{18} and plate c' return the parts to the positions 45 shown, and the parts are operated as explained previously.

We will now assume that the piston C is stopped midway of one of its strokes and that it is desired to reverse the movement of 50 the piston within the chamber a^4 . We will assume that the piston was moving away from the mechanism D, therefore steam was being admitted to the chamber a^4 by way of the duct a^7 . The lever b is now actuated 55 so as to move the valve member b^2 to such a position that the groove b^6 formed in the valve member b^2 places the annular grooves a^{12} and a^{13} in registration, wherefore the annular grooves a^{11} and a^{15} will be in communication by way of the bore formed through 60

the valve member b^2 . We will now assume that steam is again turned on. The path of the steam which formerly was by way of annular grooves a^{13} and a^{11} is now changed so that the steam entering by way of annular groove a^{13} is now directed into the annular groove a^{12} and therefore passes by way of the duct a^8 to that portion of the cylinder chamber a^4 between the piston C and the cylinder head a' , wherefore the piston C is moved toward the mechanism D. When the piston C has reached the end of its stroke toward the mechanism D, the movement of the piston is stopped by the inability of the piston to move further. The change of 70 stroke is of especial value in engines used on locomotive stokers and similar devices, wherein foreign objects may lodge between the conveyer parts and the parts of the stoker placed under great torsional strain as 75 a result of such jamming. The reversing of the piston as disclosed is sufficient to relieve the torque of the various elements acted upon by the engine.

What I claim is:

1. The combination with a reciprocating engine having ducts leading to the opposite ends of the cylinder chamber and having other ducts leading to a valve adapted to alternately exhaust and place in communication with a source of energy the last mentioned ducts, of a housing having a bore therein and having a series of spaced annular grooves communicating with the bore, one each of the grooves communicating with one each of the ducts, the alternate annular grooves communicating with the ducts of a given series, and means within the bore adapted to establish and to vary the communication between adjacent ducts, whereby either duct of the first series may be placed in communication with either duct of the second series.

2. The combination with a reciprocating engine having ducts leading to the opposite ends of the cylinder chamber and having other ducts leading to a valve adapted to alternately exhaust and place in communication with a source of energy the last mentioned ducts, of a housing having a bore therein and having a series of annular grooves communicating in alternate sequence with the ducts of the first and second mentioned series, a sleeve mounted within the bore and having ports establishing communication between the annular grooves and the bore within the sleeve, and a valve member slidably mounted in the sleeve adapted to establish communication between the ports communicating with the adjacent annular grooves.

3. The combination with a reciprocating engine having ducts leading to the opposite ends of the cylinder chamber and having other ducts leading to a valve adapted to

alternately exhaust and place in communication with a source of energy the last mentioned ducts, of a housing having a bore therein and having a series of annular grooves communicating in alternate sequence with the ducts of the first and second mentioned series, a sleeve mounted within the bore and having ports establishing communication between the annular grooves and the bore within the sleeve, a valve member slidably mounted in the sleeve adapted to establish communication between the ports communicating with the adjacent annular grooves, and a lever 15 adapted to actuate the valve member whereby the ports communicating with the ducts of the first series may be placed in communication with ports communicating with the ducts of the second series.

20 4. The combination with a reciprocating engine having ducts leading to the opposite ends of the cylinder chamber and having other ducts leading to a valve adapted to alternately exhaust and place in communication with a source of energy the last mentioned ducts, of a housing having a bore therein and having a series of annular grooves communicating in alternate sequence with the ducts of the first and second mentioned series, a sleeve mounted within the bore and having ports establishing communication between the annular grooves 25 and the bore within the sleeve, a valve member slidably mounted in the sleeve and having an axial bore therethrough and a circumferential groove, the axial bore being adapted to establish communication between the opposite ends of the bore in the sleeve and the circumferential groove being adapted to establish communication between adjacent ports in the sleeve, and a lever adapted to slidably actuate the valve member in the sleeve.

30

35

through and a circumferential groove, the axial bore being adapted to establish communication between the opposite ends of the bore in the sleeve and the circumferential groove being adapted to establish communication between adjacent ports in the sleeve.

5. The combination with a reciprocating engine having ducts leading to the opposite ends of the cylinder chamber and having other ducts leading to a valve adapted to alternately exhaust and place in communication with a source of energy the last mentioned ducts, of a housing having a bore therein and having a series of annular grooves communicating in alternate sequence with the ducts of the first and second mentioned series, a sleeve mounted within the bore and having ports establishing communication between the annular grooves 45 and the bore within the sleeve, a valve member slidably mounted in the sleeve and having an axial bore therethrough and a circumferential groove, the axial bore being adapted to establish communication between 50 the opposite ends of the bore in the sleeve and the circumferential groove being adapted to establish communication between adjacent ports in the sleeve, and a lever adapted to slidably actuate the valve member in 55 the sleeve.

In testimony whereof, I have hereunto subscribed my name this 4th day of August, 1921.

WILLIAM T. HANNA.
